[57] CLAIM

The ornamental design for a bottle, as shown and described.

DESCRIPTION

FIG. 1 is a top plan view of a bottle showing our new design;

FIG. 2 is an elevational view, the opposite side being the same in appearance;

FIG. 3 is a view looking from the right of FIG. 2, the opposite side being the same in appearance;

FIG. 4 is a sectional view taken on the line 4—4 of FIG. 2;

FIG. 5 is a bottom plan view;

FIG. 6 is an elevational view showing a modified form of our new design, the opposite side being the same in appearance;

FIG. 7 is a top plan view;

FIG. 8 is a view looking from the right of FIG. 6, the opposite side being the same in appearance;

FIG. 9 is a sectional view taken on the line 9—9 of FIG. 8; and

FIG. 10 is a bottom plan view.
